UNITED STATES PATENT OFFICE

2,496,013

PIERCING CUTOFF MACHINE

Hubert A. Myers, Toledo, Ohio, assignor to The
Toledo Steel Tube Company, Toledo, Ohio, a
corporation of Ohio

Application September 14, 1944, Serial No. 554,102

4 Claims. (Cl. 164—60)

1

This invention relates to automatic equipment for carrying thru a prescribed sequence of operations in a cycle, the specific embodiment of the disclosure having to do with the handling of tubular stock to be severed into prescribed length sections.

This invention has utility when incorporated in tubular stock piercing and cutting, for accuracy in predetermined length sections. The stock as fed up, either manually or by power, forthwith puts the machine in operation for gripping such stock, at once the trip acts for the length as set. When the stock is gripped or locked in the machine, a tool point or piercer is thrust thru the tube wall. The cutting depth as thus determined is followed up by a locking of the piercer radially as to the stock and a once-around relative turning had, in effecting complete severance of a section, or peripheral cut, in the event such be for predetermined grooving. There is no over-running, but the machine is stopped and the stock released for a resetting. With stock as much as five inches in diameter, the cut-offs have been in the range of twenty to twenty-five per minute. When smaller stock be handled, with likewise less mass to be shifted intermittently, a nearly doubled rate may be effective in practice.

Referring to the drawings:

Fig. 1 is a control diagram showing cooperating portions of the invention embodiment in a tube piercer and cut-off machine; the general position of the parts being in the rest position as the machine is about to start in thrusting the piercer;

Fig. 2 is a fragmentary plan view of portions of the machine of Fig. 1, at the general position of the severing operation just completed, but prior to release of the stock; and

Fig. 3 is a partial end view from the cut-off stock discharge side, showing the general relation of the parts as in Fig. 2.

Stock gripping

Power supply lines 1, 2, may be of 220 volt 60 cycle alternating electric current. A conductor line 3 therefrom extends to a switch 4. As tubular stock 5 is thrust thru the machine, at an adjustable predetermined position in the machine, such fed in tube 5 may strike an arm 6 to swing such on its bearing 7. A compression helical spring 8 holds the cylindrical bearing providing end of the arm to have its cam side 9 of the arm 6 against a coaxial fixed cam 10. The arm 6 as moved by the thrust of the stock 5, is moved

axially somewhat analogous to a one-way jaw clutch by the cams 9, 10, effective to have a lug 11 fixed with the arm 6 act on the switch 4 to close contact with companion switch element 12 thereby connecting a conductor line 13 thru a solenoid device 14 and line 15 to the line 2. The circuit is therefore closed for energizing the device 14 of a four-way switch device (which may be of the type of U. S. Patent 2,300,263, Oct. 27, 1942) to connect power fluid, as compressed air from the line 16 to flow thru a line 17 to a cylinder 18 to thrust a piston rod 19 downward to carry a plate 20 with its depending square rods 21. This operation in the cylinder 18 is permitted by the valve device 23 connecting duct 24 from the lower or opposite end of the cylinder 18 to an exhaust duct 25. The arm 6, as shoved by the end of the tube 5, due to the coaction between the cams 9, 10, is rocked clear for reset along side the stock 5.

The rods 21 have wedge faces 26 and adjacent grooves 27. At the entrance and exit side of the machine there are semi-cylindrical grip or clamp members 28 for the stock 5. The wedge faces 26 of the respective rods 21 in pairs as toward each other, act upon complementary wedge faces 29 of the blocks or members 28 during the descent of the piston rod 19 to clamp or lock the work or tube stock 5 with the machine. Thereafter, upon the completion of the cutting off operation and the recover or up travel of the piston rod 19, a rib 30 on the member 28 coacts with the groove 27, in thereby providing for positive release upon ascent of the rods 21.

Machine starting

At once the stock 5 be clamped or gripped, the plate 20 brings a switch element 31 into contact with a companion switch element 32. Electric circuit is thereby completed from the line 31 thru the elements 31, 32, as supplied by a branch line 33 from the line 3 a line 34 from this switch 31, 32, extends to a solenoid 35 having a line 36 therefrom to the line 15.

The energized solenoid 35 overcomes the throw or holding action of a torsion spring 37 and pulls a dog 38 clear of a stop 39 of a single rotation clutch 40 (which may be of the type of U. S. Patent 2,140,737; Dec. 20, 1938), thereby to connect a drive wheel 41 to turn a shaft 42 one full 360°.

Machine stop and stock release

As this cycle of operation nears completion, a lug 43, which may be fixed with the shaft 42, in the clockwise rotation of such shaft, rides under

a switch element 44 to swing such to closed position with a companion switch element 45. To nullify the action of the till-now closed switch 11, 12, from 3, a line 47 is now connected up thru the switch 44, 45, with a line 48 to the line 13, thereby effecting a selected different operation of the solenoid device 14 in the device 23, bringing about a second shift to the former starting position, which is power fluid from the line 16 by way of the line 24 to the cylinder 18, now exhausting from the line 17 by way of the line 25. The plate 20 is now lifted, timely releasing the dog 38 to engage the stop 39, and with the lifting of the plate 20 there is pulling of the wedge blocks 28 to free the stock 5, not only as to the cut-off section as in advance, but release of the major length follower section of the tube 5. With the tube 5 clear of the arm 6, it returns to initial position and the switch 11, 12 is opened.

Piercer mounting and actuation

Bearings 49 mount the drive shaft 42 in the housing 50 (Fig. 2). On the shaft 42 and fixed therewith in the housing 50 is piercer operating cam 51 with a gear on each side thereof having a toothed portion 52 and an untoothed portion 53. The cam 51 is shown partly broken away in Figure 1 to disclose parts covered thereby. The shape of the cam 51 is as shown in Figure 3. Axially parallel thereto, bearing providing members 54 are fixed with the frame 50. Offset toward each other and clear of the stock 5, collars from the members 54 provide support for antifriction bearings mounting the toothed rings of a pair of gears 55 assembled by a pair of intermediate disks 56 into a unit. These disks 56 form therebetween a slide guide 57 (Fig. 1) for a tool carrier 58. A lock plate 59 locates a piercing tool 60 in the carrier 58 in such segment shallow relation as to approach tangency just inward from the tube inner wall, when for severing in lieu of groove depth cutting in cylindrical stock.

The carrier 58 near the lock plate 59 has a roller 61 on a mounting shaft or pin 62. This portion of the carrier 58 as protruding from between the disks 56 extends between the members 52, 53, there to have the roller 61 contacted by the cam 51 in the rotation from starting position (Fig. 1). The tool point 60 is thus thrust thru the wall of the tubular stock 5.

Holding piercer thrown for turning operation

The disks 56, in addition to the slide guide 57, have parallel thereto a radial guide way 63 for a rib portion 65 of the carrier 58 which carrier has an intermediate web portion in which the tool 60 is mounted. The rib 65 toward the roller 61 has an arc face 66 (Fig. 1). While the carrier 58 is mounted for sliding movement between the pair of disks 56, each of the disks 56 on its face toward the web portion of the carrier 58 has a pivot bearing 67 for a swing dog 68. The arc overhang inner face of the dog free end is adapted to be pulled over the arc cam face 66 of the carrier 58, as the tool 60 is thrust to operative position. In this travel, the dog 68 is pulled by a tension spring 69 against the side of the rib 65 until it reaches the face 66, when it at once snaps into holding position, and the nose of the cam 51 is then free of the roller 61.

In practice the number of teeth on the members 52 is the same as on the gears 55, which latter gears 55 are also incomplete, each having a relatively short concave arc portion 69' to seat

with the convex untoothed portions 53. For instance seventy-five teeth in the members 52 as meshing with seventy-five teeth in the gears 55, insures driving of the disks 56 from a rest position of starting with the concave portions 69' seating at one portion of the convex arc portions 53 to another position of registry therebetween to hold the driven gears 55 and the disks 56 from rotation relatively to the frame 50. During this seventy-five teeth meshing drive, the tool 60 has a turning operation cutting action about the fixed stock 5, from the point of piercing back thereto in 360° for a full cut off. In the event the severed stock not break up, its total length is for but a single circle.

Stop lock for driven tool carrier disks

Carried by the frame 50 are slide guides 70 for sliding dogs 71. The outer faces of the wheel members 52, 53, have endless groove cam ways 72, with which dog 71 offset ends 73 coast for thereby thrusting the dog opposite end offsets 74 into the path of lugs 75 upon the outer face of the gears 55. The lugs or stops 75 are located to strike the dogs 71 as the gears 55 run off their toothed portions to the concave portions 69'. There is thus provided a supplemental automatic holding means for the work and cutting tool at rest, notwithstanding the drive shaft 42 be still turning. The counter clockwise rotation of the disks 56 is thus completed for a single cycle of a complete rotation.

Piercer withdrawal

Upon the faces of the members 52, 53 as toward each other, and near the commencement of the untoothed portions 53 as coming in from clockwise rotation, cams 76 at the down ends push swing dogs 68 against the resistance of the springs 69 to move clear of the faces 66, while arc portions 77 from the radially inward portions of these cams engage the roller bearing pin 62 to pull the roller 61 toward the shaft 42 and thereby withdraw the carrier 58 from piercing position in the tube 5. As the dogs 68 ride clear of the cam ends 76, the carrier 58 is shifted sufficiently for the dogs 68 in their recover pull from the springs 69, to ride against the adjacent side of the rib 65.

As the full withdrawal of the tool 60 approaches, or is fully achieved, the lug 43 has acted thru the switch 44, 45, to operate the wedge clamps 21, 23, to release the stock 5 at the entrance and exit sides.

Driven gear stop control

The position of the driven gears 55 at starting from rest is still that of being locked by the dogs 71. This locked or holding persists during the piercing effective thrust of the cam 51 for the tool 60. However as entering such interval, the cams 72 have a less radius section 78 (Fig. 3) serving to withdraw the dogs 71 to clear the lugs 75 for such interval as the lugs 75 may pass, when the dogs 71 are thrust outward to effect automatic stopping at timely position.

What is claimed and it is desired to secure by Letters Patent is:

1. A tube piercing and cut-off machine comprising a pair of spaced work-gripping means, a tool carrier relatively rotatable therebetween, actuating means for thrusting the tool adjacent a tangent of the tube into work piercing position, a drive for effecting relative rotation between the carrier and gripped work, and a control stopping the drive when the tool in extended piercing position, completes a cut-off operation.

2. A single revolution cut off device to sever tubular stock, comprising, means to hold the stock stationary, a tool to pierce and cut said stock, a 5 slideable tool holder, a rotatable means in which said slideable holder is slidably mounted, means to impart a thrust to said holder and tool to pierce said tubular stock, means to give a single rotation to the means which carries the slideable holder, said thrust means being located outside the orbit of rotation of said means that carries the slideable tool holder but engageable with said holder.

3. A cut off device for tubular stock comprising a clamp to hold said tubular stock stationary, reciprocable means to operate said clamp, means rotatable about said stock, a tool holder slideable in said rotatable means, a piercing and cut off tool carried by said tool holder, means to impart a thrust to said holder and tool to pierce said stock, means to give a single rotation to said rotatable means to cut the stock by said tool, said thrust means being outside the orbit of rotation of said rotatable means but engageable with said tool holder to impart said thrust.

4. A cut off device for tubular stock comprising

a sectional clamp to hold the stock against rotation relatively thereto, tool carrying means mounted outwardly from the periphery of the clamped stock, a tool holder slideable in said means toward and from the stock, a piercing and cut off tool carried by said tool holder, control means to impart a thrust to said holder and tool to cause the tool to pierce said stock, and power means to give a single relative rotation to said carrying means relatively to said stock.
